CLAIM

The ornamental design for a timepiece face, as shown and described.

DESCRIPTION

FIG. 1 is a top plan view of a timepiece face showing my new design in an energized condition showing a typical time indication for 4:05 A.M. o'clock, the dot-dash showings being environmental only and form no part of the claimed design;

FIG. 2 is a typical side elevation view thereof, the dot-dash showings being environmental only and form no part of the claimed design; the side not being generally visible when the face is held within the outer case environment, the opposite side elevation view being a substantial mirror image thereof;

FIG. 3 is a front elevation view of another embodiment of the timepiece face of my invention, showing a typical time indication of 7:10 P.M. o'clock, the dot-dash showings being environmental only and form no part of the claimed design; and,

FIG. 4 is a typical side elevation view, thereof; the side not being generally visible when the face is held within the outer case environment, the opposite side elevation view being a substantial mirror image thereof.
